IMPROVED HEATING STOVE.

LEWIS BRIDGE, OF YORK, PENNSYLVANIA.

Letters Patent No. 60,132, dated December 4, 1866.

SPECIFICATION.

TO ALL WHOM IT MAY CONCERN:

Be it known that I, LEWIS BRIDGE, of York, York county, State of Pennsylvania, have invented a new and useful improvement in Heating Stoves; and I do hereby declare that the following is a full, clear, and exact description thereof, which will enable others skilled in the art to make and use the same, reference being had to the accompanying drawings, forming part of this specification, in which—

Figure 1 is a vertical cross-section in the line $x\ x$, fig. 2.

Figure 2 is a vertical section through the longer diameter, in the line $y\ y$, fig. 1.

Figure 3 is a horizontal section through the drum, in the line $z\ z$, fig. 1.

Similar letters of reference indicate like parts.

This invention relates to improvements in parlor fire-side heating stoves, adapted to either wood or coal, and is designed to utilize the heat by the more complete radiation into the apartment, or its direction to an upper chamber, through a suitable flue attached to the stove, of that portion in the back part of the stove which is usually absorbed in the masonry of the fire-place and lost. For this purpose, in addition to a cold-air chamber running from the bottom behind the fire-box, the back and sides of the stove, when set in a fire-place, are surrounded with a sheet-metal hood or bonnet, which also passes over the top of the stove to the front, and conducts the heat that is radiated at the back of the stove through the cold-air chamber into an open horizontal air space over the stove directly into the apartment, or up through a drum into the upper room, as aforesaid. In addition to this arrangement for utilizing all the heat of a fire, a shifting division grate is introduced into the fire chamber, in the line of the longer axis of the stove, for the purpose of changing the capacity of the fire chamber to hold and burn more or less fuel, according to the temperature of the weather, by moving its position forward and back, or removing it entirely in extremely cold weather. The stove may be made of cast or sheet iron, rectangular, or of any suitable form, but, as represented, I prefer making it oval, of sheet iron.

A represents the fire chamber, with an ordinary grate $x\ x$, and a shifting grate $a\ a$, suspended longitudinally on the top of the fire-brick lining, so that it can be moved to the front or rear more or less, as required, the side lining being made nearly or quite straight from the front to the rear of the fire chamber, for the purpose. The base B, which sets upon legs $b\ b$, as usual, is surrounded with a perforated shield or guard $c\ c$, and contains the ash pan C. At the back of the fire chamber A, extending from the base to the top of the stove, is a jacket, $e\ e$, enclosing a vertical air space D, open at the bottom for the entrance of cold air, and at the top for the passage of the warmed current of air passing through into another horizontal air space E over the fire chamber, and under a flat horizontal annular drum F. At the back part of the fire-chamber A are placed two exit flues G G', direct and indirect, which pass through the air space E up into the annular drum F, and are provided with dampers $f\ f'$, their rods $d\ d'$ extending across to the front of the stove, to regulate the course of the products of combustion. When the flue G is closed and G' is open, the products of combustion pass directly up into the exit pipe H to the chimney; but when G' is closed and G is open, they are diverted in their course by a partition g, and pass around the annular drum F, to make their final escape through the pipe H, after radiating their heat. Behind and over the stove, extending from the back nearly to the front, is placed an independent sheet-iron or tin hood $h\ h$, enclosing an air space I, which surrounds the back and sides of the stove and the top of the annular drum F. In the upper part of the hood $h\ h$ provision is made for a conducting flue K, shown in red, which may be connected, if desired, for conveying the heated air from the air spaces E and I into an upper chamber, to be regulated in its passage by the damper i on the rod j. By this arrangement it will be seen that none of the heat is lost by absorption in the back of the fire-place, and that it will be as completely utilized in warming an apartment as if the stove was sitting out in the room, while the consumption of more or less fuel, according to the temperature, may be perfectly regulated by the shifting grate $a\ a$, thus utilizing all the heat and economizing fuel. The course of the heated air around the stove is also governed by the damper i, and may be thrown into the room, or conveyed to an upper chamber, at pleasure.

Having described my improved parlor fire-place heating stove, what I claim as new, and desire to secure by Letters Patent—

I claim the arrangement of a parlor fire-place heating stove, with a vertical cold-air space D around the back of the fire chamber A, in combination with the surrounding hood $h\ h$, for utilizing the heat radiated from the rear of the stove and conducting it into the room, or to an upper chamber, when desired, constructed and operating substantially as and for the purposes herein described.

The above specification of my invention signed by me this 5th day of July, 1866.

LEWIS BRIDGE.
